CLAIM

The ornamental design for a lottery card marker, as shown and described.

DESCRIPTION

FIG. 1 is a perspective view of a lottery card marker showing my new design;

FIG. 2 is a left side elevational view thereof, the right side being a mirror image;

FIG. 3 is a top plan view thereof;

FIG. 4 is a bottom plan view thereof;

FIG. 5 is a front elevational view thereof; and

FIG. 6 is a rear elevational view thereof.

The broken line showing in FIG. 1 is for environment only and forms no part of the claimed design.

*fig. 1**fig. 2*

*fig. 3**fig. 4**fig. 5**fig. 6*
